UNITED STATES PATENT OFFICE.

GEORGE W. RUSH, OF ALTOONA, PENNSYLVANIA.

DESIGN FOR A GARMENT-SUPPORTER.

SPECIFICATION forming part of Design No. 32,355, dated March 20, 1900.

Application filed January 11, 1900. Serial No. 1,153. Term of patent 14 years.

To all whom it may concern:

Be it known that I, GEORGE W. RUSH, a citizen of the United States, residing at Altoona, in the county of Blair and State of Pennsylvania, have invented and produced a certain new and original Design for a Garment-Supporter; and I do declare the following to be a full, clear, and exact description of the invention, such as will enable others skilled in the art to which it appertains to make and use the same.

The invention relates to a new and original design for a garment-supporter; and it consists of a design of the shape and configuration shown in the accompanying drawings, in which—

Figure 1 is a plan view. Fig. 2 is a side elevation.

The leading feature of the design is the ap-

proximately-triangular body portion formed by members 2' 2' and 3 3, the latter being twisted around each other at their upper ends, as shown at 4, and one being provided with an angular extension 5 and the other with a hook-pin formed by the parts 6, 7, and 8. The lower ends of the members 2' 2' terminate in a loop formed by the diverging arms 1 2.

What I claim is—

The design for a garment-supporter, substantially as herein shown and described.

In testimony whereof I have hereunto set my hand in presence of two subscribing witnesses.

GEORGE W. RUSH.
